FLOOR FURNACE GAS CONTROL MEANS

Lourdes V. McCarty, Milwaukee, Wis., assignor to
 Milwaukee Gas Specialty Company, Milwaukee, Wis., a corporation of Wisconsin

Application March 4, 1943, Serial No. 477,942

14 Claims. (Cl. 236—1)

This invention has to do with means for controlling flow of fuel to a burner, such means being particularly suitable for use in connection with floor furnaces and analogous devices.

My invention is directed to control means of the character referred to having safety means for automatically shutting off flow of fuel to a main burner and, preferably, to an associated pilot burner, in the event of extinguishment of the pilot burner or of both burners due to temporary interruption of flow of fuel, blowing out of the burners, such as might be caused by an exceptionally high draft, or other causes. I provide control means of the character stated comprising a thermal control for automatically regulating flow of fuel to the main burner in accordance with variations in temperature of the fluid heated thereby, and also provide means whereby the flow of fuel to the main burner may be controlled manually independently of the thermal control when desired. The placing of the flow of fuel to the main burner under control of thermal responsive means, or under manual control, is effected by adjusting means, the latter means being effective for completely shutting off the flow of fuel to the main burner independently of the thermal responsive means, when desired. More specifically, I provide a safety valve controlling flow of fuel to the main burner and to the pilot burner, and a valve controlling flow of fuel to the main burner, the safety valve being urged in closing direction and normally held open by electromagnetic means energized by a thermoelectric generator subjected to the heat of the pilot burner so that, upon extinguishment of the pilot burner, the safety valve automatically closes, shutting off supply of fuel to both burners. The main burner valve normally is operated by thermal responsive means but may be operated manually, as above stated, by proper adjustment of the adjusting means, and the latter means may be operated to trip the safety valve causing closing thereof and may also be operated to reset the safety valve into its open position in which it normally is held by the electromagnetic means, when the pilot burner is lighted and the coil of the electromagnetic means is energized by the thermoelectric generator heated by the pilot burner. I also provide means for causing opening and closing of the main burner valve with a snap action, assuring safe and satisfactory operation thereof. Further objects and advantages of my invention will appear from the detail description.

In the drawings:

Figure 1 is an isometric sectional view of a floor furnace with control means embodying my invention applied thereto, parts being broken away and the floor structure being shown fragmentarily with a register supported thereby overlying the furnace;

Figure 2 is a plan view, on an enlarged scale, of the control means of my invention;

Figure 3 is a sectional view taken substantially on line 3—3 of Figure 2, certain parts being shown in elevation and certain other parts being broken away;

Figure 4 is a sectional view taken substantially on line 4—4 of Figure 3;

Figure 5 is a sectional view taken substantially on line 5—5 of Figure 3, certain parts being shown in elevation and the housing being shown as partly broken away, on an enlarged scale;

Figure 6 is a sectional view taken substantially on line 6—6 of Figure 3, certain parts being shown in elevation and certain other parts being broken away, on an enlarged scale;

Figure 7 is a detail underneath view, on an enlarged scale, of the main valve operating lever;

Figure 8 is an axial vertical sectional view of a modified form of thermostat and associated parts, parts being shown in elevation and certain other parts being broken away and the top wall of the housing being shown fragmentarily;

Figure 9 is an axial vertical sectional view of the safety valve and the electromagnetic means associated therewith and associated parts, the adjacent portion of the housing being shown in section, this view being on an enlarged scale; and

Figure 10 is a diagram showing the different positions of the adjusting means.

In Figure 1 I have illustrated the control means of my invention as applied, by way of example, to a floor furnace *f*. This furnace may be of any suitable known construction and a brief description thereof will suffice. The furnace comprises an outer casing *11* within which is disposed an intermediate casing *12*, which may be of double walled construction for the major portion of its length, the bottom edge of the intermediate casing *12* being spaced from the bottom wall *13* of casing *11*, defining therewith an opening *14*. The space between the casings *11* and *12* defines a cold air return passage *15* opening at its lower end, at *14*, into casing *12* and, at its upper end, through the outer portion of a register *16*, supported in overlying relation to the furnace by floor *17*, from which the furnace *f* depends. An inner casing *18* is disposed within casing *12* in spaced relation thereto, defining

therewith a heated air passage 19. The upper portion of casing 12 is inclined upward and inward, as shown, and defines a heated air opening 20 through which heated air flows upward through the inner portion of register 16. The inner casing 18 is provided with an outlet 21 for the products of combustion, which may be connected by a pipe (not shown) to a chimney, in a known manner, and is also provided with an interior lining 22 of fire brick or other suitable refractory material.

A main gas burner 23 is suitably supported within the inner casing 18 and provides the heat source for the furnace, this main burner having a conduit 24 extending therefrom for supplying gas thereto. A pilot burner 25 is mounted on main burner 23 by a bracket 26 secured thereto, this bracket also serving to support a thermocouple 27 in position adjacent the pilot burner, the latter being provided with suitably disposed jet openings for directing a flame toward the main burner for igniting the latter, and a flame against the thermocouple 27 for heating the latter, for a purpose which will appear presently. It will be understood that when the main burner 23 is in operation, relatively cold air flows through the outer portion of register 16 downward through passage 15, thence through opening 14 into the heated air passage 19, this air flowing about the combustion chamber defined by the inner casing 18 so as to be heated thereby, the air thus heated then flowing upward through the inner portion of register 16. Preferably, the outer casing 11 is provided with a suitable opening 28 for supplying fresh air in suitable proportion to the air in passage 15. The inner casing 18 may also be provided, at the top thereof, with an inspection opening normally closed by a hinged lid or cover 30. It is to be understood that the furnace shown and above described is by way of example only and that any other suitable known floor furnace may be used. Also, as noted, the control means of my invention, while particularly suitable for use in connection with floor furnaces, is not limited to such use and may be used to advantage for many other purposes.

The control mechanism of my invention is conveniently disposed within an appropriately formed housing 35, which may be substantially cubiform as shown. Housing 35 is provided at one side thereof with a cover plate 36, with an intervening gasket 37, cover plate 36 being secured to the housing by screws 38, beneath the heads of which are disposed spring washers 39. Cover plate 36 is readily removable to give access to the parts within housing 35, and the latter is provided at one end thereof with an integral nipple 40 for reception of a pipe 41 screwing thereinto. Nipple 40 opens into housing 35 through an inlet opening 42 thereof, through which opening the fuel, which may be fuel gas, is admitted to housing 35 under control of a safety valve, as will be explained presently. Housing 35 is further provided, at its lower wall, with an integral downwardly extending nipple 43 which is interiorly threaded, into which nipple is screwed an outlet pipe 44 leading to conduit 24 of the main burner 23 of furnace 1. The outlet pipe 44 is provided at its other end with a tip member (not shown), extending into a mixing chamber 45 at the outer end of conduit 24, this mixing chamber having an adjustable plate or disc for regulating the amount of air admitted thereto for mixture with the gas, as is well known. Communication of inlet opening 42 with the interior of housing 35

is controlled by a safety valve, as above stated, and communication between outlet pipe 44 and the interior of housing 35 is controlled by a main burner valve, as will be explained more fully later, and when these two valves are opened gas may flow from pipe 41 into housing 35 and from the latter through pipe 44 to the main burner 23.

Housing 35 is provided interiorly thereof with a hollow boss 46 (Figure 3) defining an inlet chamber in free communication, through inlet opening 42, with nipple 40 and inlet pipe 41. Boss 46 is provided, through its top wall, with a valve port 47 the lower portion of the surrounding wall of which is shaped to provide a seat for a downwardly opening and upwardly closing safety valve member 48. A valve stem 49 is loosely secured at its upper end, by a pin 49^a (Figure 9), to valve member 48 and extends downward therefrom into a thermo-electric control device associated with a tubular element or sleeve 50 of step formation interiorly, as shown, extending downward from the bottom wall of housing 35 in alignment with the boss 46. The thermo-electric control device may be similar to that disclosed in the patent issued to Clarence Wantz on January 12, 1943, No. 2,307,870. The thermo-electric control device includes a lead connection cap and magnet and armature housing assembly mounted upon the lower end of sleeve 50 and closing the latter. The lead connection cap 52 is formed of any suitable or preferred known insulating material and is provided, at its upper portion, with a cylindrical extension 53 which fits snugly within the lower portion of sleeve 50. Cap 52 is secured to sleeve 50 in any suitable manner, conveniently by means of screws (not shown), passing through cap 52 and threading into sleeve 50, there being an intervening gasket 54 providing a fluid tight seal between the cap and the sleeve. A magnet 55, in the form of a downwardly opening cup-shaped metal shell, is mounted in extension 53 of cap 52 in a suitable manner, conveniently by having a pressed fit therein. The upper portion 56 of housing 55 is slightly reduced in diameter and has a pressed fit in the lower portion of an armature housing 57, in the form of a cup-shaped metal shell similar to housing 55. Valve stem 49 is slidable through the upper end of armature housing 57, and through a disc 59 thereabove seating against an annular shoulder 60 at the lower end of boss 46. Packing material 61, which may be felt or any other suitable material, is confined between the upper end wall of armature housing 57 and disc 59, and is held under compression by a compression spring 62 mounted about valve stem 49 and confined between valve member 48 and disc 59, the latter being provided with a central upwardly extending projection 63 coaxial with neck 64 of valve member 48, to which neck 64 valve stem 49 is attached by pin 49^a, the projection 63 and neck 64 receiving the end portions of spring 62 and centering the latter. The upper end of valve stem 49 preferably has slight clearance in the valve member 48, having a certain amount of looseness therein and facilitating accurate seating of this valve member. It will be seen that the compression spring 62 urges valve member 48 upward in closing direction and also serves to compress the packing 61 about valve stem 49 so as to provide a fluid tight seal thereabout, as above noted.

An armature 66, of disc shape, is secured on the lower end of valve stem 49, within the armature housing 57, the attachment of this armature to stem 49 being sufficiently loose, as indicated at 67,

to permit relative movement of armature 66 sufficient to assure accurate seating thereof on the pole ends of the frame of an associated electromagnet.

The electromagnet comprises a magnet frame 69 of elongated U-shape, provided centrally of its bight portion with a screw stud 70 welded or otherwise suitably secured thereto. This stud 70 extends through an opening in the lower end of cap 52, into a recess 71 therein which accommodates a nut 72 screwing onto stud 70 and having a kerf 73 therein for reception of the blade of a screw driver or other suitable tool. A spring washer 75 is disposed between nut 72 and the wall at the upper end of recess 71. The legs of magnet frame 69 extend upward, through suitable openings in the upper end of magnet housing 55, and are disposed to attract armature 66 and hold it in its lowered position, when the safety valve member 48 has been moved downward to open position, the electromagnet when energized thus holding the safety valve member open. But the electromagnet is incapable, when energized, of moving the armature 66 from its released or retracted position, shown in Figure 9, downward into its attracted position, and once the safety valve member 48 has been closed it remains closed, whether the electromagnet is energized or not, until moved downward into its open position by means to be later described, and if the electromagnet is energized at that time it holds valve member 48 in its lower or open position in opposition to the compression spring 62.

The electromagnet comprises a winding or coil 71 disposed about the legs of frame 69, within electromagnet housing 55, the ends of which coil are connected to metal terminal connectors or posts 78 and 79 fixed rigidly in cap 52, conveniently by moulding the material of the cap about the terminal connectors. The lower end portions of the connectors 78 and 79 are split and bored for reception of the terminal portions of the leads of an associated thermocouple, about which terminal portions the connectors 78 and 79 may be contracted or clamped by means of associated clamp screws 80. The thermocouple 27, shown in Figure 1 in association with the pilot burner 25 and the main burner 23, may be, in general, constructed similarly to the thermocouple disclosed in the patent to Oscar J. Leins, No. 2,126,564, issued August 9, 1938, and the terminal portions of the leads of the thermocouple may be constructed and arranged in the manner disclosed in the above identified patent to Clarence Wantz, for cooperation with the terminal connectors 78 and 79. Within the broader aspects of my invention, any other suitable thermocouple or thermoelectric generator may be employed, and any other suitable means may be provided for connecting the thermoelectric generator leads to the winding of the electromagnet. Suffice it to state that I provide a suitable thermoelectric generator the leads of which are suitably connected to the ends of the electromagnet winding, for energizing the latter responsive to heating of the thermoelectric generator.

Valve member 48 is provided with an upwardly extending neck 81 passing through valve port 47. An upper valve stem 82 is loosely secured at its lower end in neck 81, by a pin 83 restrained against endwise movement by a retainer 84 seating in a circumferential groove in neck 81. Stem 82 is provided at its upper portion with an enlargement or collar 85, conveniently formed integral therewith, above which stem 83 is reduced in

diameter at 86, the upper end portion of this stem being further reduced in diameter to provide a stud 87. An upper collar 88 is mounted about stud 87 and seats on the upper end portion of reduced portion 86 of stem 82, the upper end of stud 87 being peened over at 89, at the upper face of collar 88 which is thus secured on stud 87 and confined against relative axial or endwise movement. It will be noted that the opposed faces of collars 85 and 88 are oppositely inclined defining between them an annular channel of V-shape in cross section. Element 86 of stem 82 passes through an opening 91, of appreciably greater extent than element 86, in the outer end portion of a safety valve trip and reset lever 92, pivoted intermediate its ends on a shaft 93 extending transversely of housing 35, as shown in Figure 6. Shaft 93 has its end portions reduced in diameter and one end thereof is mounted in a boss 94 formed integrally with the adjacent side wall of the housing 35, the other reduced end portion of shaft 93 extending through a spacer 95 disposed at the inner face of a retaining plate 96, in which such end portion of shaft 93 is mounted. The retaining plate 96 is of irregular polygonal shape, as indicated in dot and dash lines in Figure 3, and is secured in any suitable manner, conveniently by screws, to boss 46 and thickened portion 97 of the top wall of housing 35. It will be seen that lever 92 is mounted for rocking movement about the axis of shaft 93 and that movement of this lever in clockwise direction, as viewed in Figure 3, will move the safety valve member 48 downward, movement of lever 92 in counterclockwise direction resulting in upward movement of valve member 48 into its closed position, shown in Figure 3, as will be explained more fully later.

Lever 92 is of channel cross section for the major portion of its length, and is provided, at one side and at its inner portion, with an inwardly extending projection 99 outwardly offset laterally of the body of lever 92. Projection 99 is provided with an upper finger 100, which may be termed a reset finger, and a lower finger 101, which may be termed a trip finger. A shaft 103, mounted in tabs 104 depending from an adjusting lever 105 of channel cross section, extends between fingers 100 and 101 for contact therewith, this shaft being restrained against endwise movement by one side wall of housing 35 and a stop pin 106 secured in shaft 103 adjacent the other end thereof, as shown more clearly in Figure 5. Lever 105 is pivoted, at the end thereof adjacent valve stem 82, on a transverse shaft 108 passing through hub elements 109 of lever 105, the end portions of shaft 108 being reduced in diameter and one of such end portions being mounted in a boss 110 integral with one side wall of housing 35, as shown in Figure 6, the other end portion of shaft 108 being mounted in the retaining plate 96. Lever 105 is provided, at its underside and adjacent its other end, with a centering disc 111 welded or otherwise suitably secured thereto, about which seats the upper end of a compression coil spring 112 the lower end of which seats about a boss 113 integral with and extending upward from the bottom wall of housing 35, boss 113 being coaxial with an exterior boss 114 extending downward from this wall. The bosses 114 and 113 are suitably bored and threaded for reception of the end portion of a tube 115 screwing thereto, this tube being connected to the pilot burner 25 for supplying fuel thereto. The compression spring 112 urges adjusting lever 105 up-

ward in a clockwise direction about the axis of shaft 103, as will be clear from Figure 3, while permitting ready flow of gas between the convolution of this spring and thence through tube 115 to the pilot burner.

One of the tabs 104 of the adjusting lever 105 is provided with an integral downward extension 118 of substantially triangular shape, shown more clearly in Figure 3. A main burner valve regulating lever 117 is pivoted on shaft 103, by means of tabs 119 formed integrally with lever 117 and depending therefrom adjacent the inner faces of tabs 104 of lever 105. Lever 117 extends downward from shaft 103 at an inclination thereto toward boss 46 and has its intermediate portion bent upward at an angle at 120, as shown. The upper portion of regulating lever 118 is formed to provide a downwardly extending element 121, defining a recess 122 of inverted conical shape for reception of an associated point member, as will be explained more fully later.

The lower end portion of regulating lever 117 bears upon an arcuate spring tongue 124 struck from a main burner valve operating lever 125, this lever having two lateral arms 126 extending therefrom toward boss 46. Each arm 126 is riveted or otherwise secured to the outer portion of bushing 128, which outer portion is of increased diameter, as shown. The bushings 128 receive a shaft 130, mounted for rotation at one end in a suitably bored stud 131 secured in the side wall of housing 35 remote from retaining plate 96, the inner end portion of stud 131 extending into a corresponding recess in the outer end of the adjacent bushing 128. The other bushing 128 is provided in its outer face with a recess concentric with shaft 130, which recess receives the inner portion, of increased diameter, of a bushing 132 having a reduced neck inserted through retaining plate 96, the outer end of this neck being spread or peened over at 133 for securing bushing 132 in plate 96. Shaft 130 is of such length, and the portion of this shaft extending into stud 131 is of such length, that cover plate 36 is effective for preventing accidental endwise displacement of shaft 130 sufficiently to withdraw the latter from stud 131. A main burner valve carrying lever 135 is mounted on shaft 130, by means of tabs 136 extending upward from lever 135 at each side thereof, these tabs 136 being spaced from the inner ends of bushings 128 by spacers 137 extending about shaft 130. The main valve operating lever 125 and the main valve carrying lever 135 are thus mounted on shaft 130 for independent movement about the axis of this shaft.

Lever 125 is provided, at one side of its other end, with a relatively narrow extension 139, as will appear more clearly from Figure 7, this extension being provided, intermediate its length, with a depressed element 140 and, a short distance beyond this element, being bent to provide a terminal element 141 of substantially inverted U-shape, as shown more clearly in Figure 3. A screw 142 threads through the inner arm of element 141, with its head contacting the outer face of the outer arm of this element, for adjusting the distance between the arms thereof. The outer arm of element 141 is provided, at its lower end, with a reduced stud 143 which extends through a corresponding opening in a tongue 144 at the outer end of a leaf spring 145. A plate 146 of generally triangular shape is riveted to the under face of lever 125 with its body portion offset

downward relative thereto, as shown more clearly in Figure 3, this plate having a centering disc 147 secured thereto at its under face adjacent the inner end of extension 139. Plate 146 also is provided, outward from disc 147, with a circular opening 148 underlying the mid-portion of spring 145. At its other end, extension 139 is provided with a downwardly directed finger 149 having a reduced stud 150 extending through a corresponding opening in a tongue 151 at the other end of spring 145. The offset portion of plate 146 defines with depressed element 140 of extension 139 a slot through which the spring 145 passes. A stop screw 152 (Figure 3) is threaded through nipple 43 and is formed at its upper end portion to provide a reduced stud 152a aligned with opening 148, substantially coaxially therewith. A coil compression spring 153 is confined between plate 146 and the bottom wall of housing 35, the upper end of this spring seating about disc 147 and the lower portion thereof seating about a centering stud 154 projecting upward from the bottom wall of housing 35. The stop screw 152 and spring 145 and associated parts are so related that the regulating lever 125 has a snap action as it approaches the limit of its downward movement and as it starts its upward movement, as will be explained more fully later.

Lever 135 carries, at its other end, a valve disc 155 which flares downward at its under face, for seating upon seat element 156 of a valve seat member 157 mounted in an upward extension 158 of nipple 43. Extension 158 may be in the form of a thickening of the bottom wall of housing 35, extending the full width thereof, and nipple 43, including extension 158, is provided with a bore of step formation providing a shoulder 159 overlying the outer portion of a flange 160 at the lower end of seat member 157. The portion of nipple 43 through which seat member 157 extends is unthreaded. Nipple 43 is internally threaded at its intermediate portion, for reception of an annular lock nut 161 screwing therein and having an axially extending circumferential rib 162 which contacts the under face of flange 160 and cooperates therewith and with shoulder 159 for securing seat member 157 in position. When valve 155 is in its closed position, shown in Figure 3, it seats upon the seat element 156 of member 157, closing the upper end of the latter member and thus preventing flow of gas from housing 35 to the pipe 44 leading to the main burner. Valve disc 155 is provided with a central upwardly extending neck 165 which fits loosely through lever 135, the upper portion of this neck being reduced, for reception of a washer 166 seating on the upper face of lever 135, the upper end of neck 165 being spread or peened over the washer 166, as shown. In that manner valve disc 155 is connected to lever 135 for movement therewith, this connection having slight play or looseness to assure accurate seating of valve disc 155 on the valve seat element 156 of valve seat member 157. Lever 135 is provided, a short distance from the valve carrying end thereof, with an integral upwardly extending arm 168 (Figure 3) provided in its inner edge with a rectangular notch 169 which receives the adjacent lateral edge portion of regulating lever 125, providing a finger 170 at the upper end of notch 169 and overlying lever 125. A leaf spring 171 is suitably secured, as by riveting, to arm 168 and has its upper portion extending therefrom at an inclination upward toward the regulating lever 118. This upper portion of spring 171 underlies the lower cor-

ner of extension 117 of the adjusting lever 105, as shown in Figure 3. During automatic operation of the control, extension 117 is spaced above spring 171, permitting movement of regulating lever 125 and the main burner valve lever 135 independently of adjusting lever 105.

The conical depression 122 of the regulating lever 118 receives the conical point element of a point member 175 screwed on the lower end of a threaded portion of reduced stem 176 (Figure 3) 10 of a plunger 177, of increased diameter, slideable in a barrel 178 having its lower end flanged inward to limit downward travel of plunger 177, as shown. At its upper end barrel 178 is provided with an outer circumferential flange 179, against 15 which seats the upper end of a coil compression spring 180 disposed about barrel 178. Spring 180 is confined between flange 179 and a nut 181 screwing on stem 176 and having an upward extension centering the lower end of spring 180. 20 A disc 182 seats upon the upper end of barrel 178 and is disposed at the upper end of a metal bellows 183 within the lower portion of a cylindrical housing 184, in the lower end of which is secured a cup 185 to which the lower end of the bellows 183 is secured so as to form a fluid tight and pressure resistant closure therewith. Cup 185 is provided with a central opening of proper size to accommodate the lower end of barrel 178 and the spring 180. Cup 185 is disposed in an enlargement at the lower end of housing 184, provided at its lower end with an outer circumferential flange 186. This flange 186 is clamped in the upper end of a boss 187 integral with the top wall of housing 35 and defining an opening through which the stem 176 and spring 180 extend, this boss having a recess in its upper end providing a shoulder between which and a clamping ring 188, secured to boss 187 by means of screws or in any other suitable manner, flange 186 is clamped, with an intervening gasket 190. The upper end of the cylindrical housing 184 is closed by a wall 191 and a collar 192 of a stop pin 193, collar 192 fitting snugly through wall 191 and being secured thereto so as to form a fluid tight and pressure resistant closure therewith, conveniently by soldering. The stop pin or post 193 is provided, adjacent its upper end, with a head 194, above which collar 192 extends, this head having a bore 195 extending transversely therethrough and communicating with an intersecting bore 196 therein extending downward through collar 192. A short filling tube 197 is secured in collar 192, for charging the housing 184 with a suitable amount of a thermosensitive fluid, such as ether, after which the upper end portion of tube 197 is flattened at 198 and sealed by soldering or in any other suitable known manner to provide a fluid tight and pressure resistant closure therefor. It will be understood that the housing 184 and associated parts, together with the charge of thermosensitive fluid therein, constitute thermostatic means for exerting downward pressure on regulating lever 118, this pressure varying in accordance with temperature variations, the post 193 providing a stop positively limiting upward expansion of the bellows 183 and also limiting upward movement of plunger 177, thereby limiting the maximum upward movement of regulating lever 118.

The top wall of housing 35 is provided, adjacent boss 187, with an upwardly extending interiorly threaded nipple 200 which receives the lower threaded portion of an adjusting screw 201 screwing therein. Screw 201 is centrally bored 75 for turning the latter in desired direction, the

and interiorly threaded for reception of an adjusting pin 202 having a threaded upper portion 202a of increased diameter screwing into adjusting screw 201. The lower unthreaded portion of stem 202 is slideable through an opening in the thickened portion of boss 97 of the top wall of housing 35, this boss being provided with a recess constituting a continuation of the bore of nipple 200 and receiving means for forming a gas tight closure about stem 201. The latter means comprises asbestos or other suitable packing material 204 confined between packing gland gaskets 205 and 206, the latter of frusto conical shape and seating in a corresponding recess in the lower end of a follower 207 urged downward by a compression coil spring 208, confined between the lower end of adjusting screw 201 and the upper face of the head of follower 207, the latter having a reduced neck for centering spring 208. Adjusting stem 202 is locked in adjustment by a set screw 209 of known type threading into screw 201 and turned into binding contact with the upper end of stem 202. It will be apparent that when the adjusting screw 201 is threaded into the neck 200 of the adjusting stem 202 will force lever 105 downward about shaft 108, in opposition to the compression spring 112, and when adjusting screw 201 is screwed out of nipple 200 lever 105 will be moved upward about shaft 108 by spring 112.

30 A pin 212 extends through adjusting screw 201 diametrically thereof, above set screw 209, and is secured in position by a set screw 213 threaded into screw 201. Pin 212 projects radially beyond screw 201 into an arcuate slot 214 in a hood 215, the body portion of which is disposed in concentric spaced relation to adjusting screw 201 and to neck 200, this hood being provided at its upper end with a reduced neck 216 fitting about and free from adjusting screw 201. Hood 215 is provided, at its lower end, with an arcuate projection 218, constituting a stop cooperating with a second stop, in the form of a stud 219 having a reduced threaded shank screwing into the top wall of housing 35. Extension 218 is provided with a T-slot 220 the stem of which opens through the lower face of extension 218, this slot receiving an outwardly bent terminal element 221, at the lower end of a torsion coil spring 222 disposed about neck 200, between the latter and hood 215. The upper end portion of spring 222 is formed to provide a hook element 223 which engages about the outer end portion of pin 212. Torsion spring 222 tends to turn adjusting screw 55 201 in a clockwise direction, as viewed in Figure 2, relative to hood 215, and normally holds pin 212 in contact with hood 215 at the clockwise or left end of slot 214.

60 Adjusting screw 201 is provided with an upper enlarged portion 225 from the upper end of which extends a reduced neck 226. Portion 225 is splayed or flattened at its opposite sides at 227 (Figure 2). For reception of a socket member 228, flattened interiorly at its opposite sides for cooperation with the flattened sides of portion 225 of adjusting screw 201. Socket member 228 is provided, in its upper portion, with a reduced bore 230 which receives neck 226 with slight clearance thereabout, and is secured to neck 226 by 65 means of a pin 231 the end portions of which extend loosely through openings in socket member 228. The flat sides of socket member 228 are spaced slightly from the flat sides of portion 225 of adjusting screw 201 and cooperate therewith 70 75 for turning the latter in desired direction, the

connections thus provided between socket member 228 and portion 225 of the adjusting screw providing a certain amount of universal movement therebetween, sufficient to accommodate any slight misalignment of the parts, while providing an effective connection for adjusting screw 201. An adjusting rod 234 is welded or otherwise suitably secured to socket member 228 and extends therefrom upward through an opening in register 16 (Figure 1), the upper end of rod 234 being squared for reception of a key 235 of known type for turning rod 234 in desired direction. Rod 234 is provided, adjacent the upper face of register 16, with a pointer 236 movable over an appropriately marked dial 237 which may be carried by the register 16, or by a plate mounted thereon. Preferably, a coil compression spring 238 is mounted about rod 234 and is confined between bottom wall 13 of the furnace 1 and an abutment, such as a washer 239, mounted about rod 234 and restrained against upward movement therealong by a cotter pin 240 secured through rod 234. Spring 238 carries the weight of rod 234 and key 235, thus avoiding any objectionable downward pressure on the adjusting screw 201 and associated parts such as might tend to interfere with effecting and maintaining desired adjustment of the control means.

The thermostat shown in Figure 8 is, in general, similar to that shown in Figure 3, but embodies certain variations for a purpose which will be explained later. Referring to Figure 8, the thermostat housing comprises a lower tubular section 242 and an upper tubular section 243, these two sections together enclosing the bellows and associated parts. Section 242 is threaded, at its lower end, into a flanged collar 244 preferably soldered, at its upper end, at 245, to housing section 242 to assure a fluid tight and pressure resistant closure therewith. At its lower end, collar 244 is provided with an outer circumferential flange 246 of step formation, the reduced lower portion of which extends into a recess in boss 187, to which collar 246 is secured, conveniently by screws 248 beneath the heads of which are disposed spring washers 249, there being a sealing gasket 250 disposed between the under face of collar 246 and the cooperating shoulder of boss 187. A collar 252, similar to collar 244, is secured upon the upper end of housing section 242 in the same manner as collar 244 is secured upon the lower end of this section. The upper housing section 243 is slightly enlarged at its lower end, at 253, and has secured therein, in any suitable known manner, as by soldering, a bellows cup 254 to which the lower end of bellows 183 is secured. At the lower end of enlargement 253 housing section 243 is provided with an outwardly extending circumferential flange 256 of substantially L-shape in cross section. This flange 256 receives a sealing gasket 257 which seats upon the upper face of flange 258 of collar 252. A clamping ring 259 seats upon the upper face of flange 256, about enlargement 253 of housing section 243, and is secured to flange 258 by bolts 260 receiving on their lower ends nuts 261, with spring washers 262 disposed between flange 258 and nuts 261. The upper housing section 243 is provided with a top wall 263 provided, at its central portion, with a nipple 264 secured therethrough in a manner to provide a fluid tight and pressure resistant closure therewith. This nipple receives an end of a tube 265 suitably secured therein, as by soldering at 266, so as to provide a fluid tight and pressure resist-

ant closure therewith. Tube 265 opens at its other end into a bulb 267 secured thereon in a known manner, this bulb being of known type and the upper housing section 243 and bulb 267 being suitably charged with a thermo-sensitive fluid, such as ether or any other suitable fluid. It will be understood that the bulb 267 may be disposed in any suitable location remote from the thermostat housing, so as to control actuation of the thermostat responsive to temperature variations at a location remote from the thermostat housing.

Stem 176^a of plunger 177^a has its lower end portion reduced in diameter and threaded to provide a screw stud 270. A stem 271 of greater diameter than stem 176^a, is suitably bored and tapped from its upper end and threads onto stud 270, in contact with the lower face of a cup washer 272 clamped between the upper end of stem 271 and the lower end of the body portion of stem 176^a. Cup washer 272 receives and centers the lower end of compression spring 180 disposed about barrel 178 and confined between flange 179 thereof and cup washer 272. The lower portion of stem 271 is threaded at 275 for reception of a point member secured thereon corresponding to the point member 175 of Figure 3. It will be understood that the point member secured on the lower end of stem 271 engages in the conical depression 122 of the main burner valve regulating lever 118 for exerting downward pressure thereon, in the same manner as point member 175 of the thermostat shown in Figure 3.

In Figure 1 the thermostat is disposed in the return passage 15 of furnace 1 and, accordingly, is subject to the temperature of the cool air returning to the furnace. With the parts in the positions shown in Figure 3, the safety valve member 48 is in its closed position, to which it has been moved by compression spring 62, and the armature 66 (Figure 9) is in its raised or retracted position spaced away from the frame 89 of the electromagnet which, when energized, is incapable of moving it downward into its attracted position and thus opening the valve member 48. Accordingly, the valve member 48 remains closed, cutting off the flow of gas to the interior of housing 35 and, therefore, cutting off the flow of gas to the pilot burner tube 115, with the result that the pilot burner 25 is extinguished. The main burner valve 155 is also in its closed position shown in Figure 3 and the main burner 23 is extinguished, flow of fuel to the latter burner being prevented so long as valve 155 remains in its closed position. With the parts in their positions shown in Figure 3, hood 215 is in its position shown in Figure 2, with the right hand end of extension 218 in contact with stop 219, and pin 212 in contact with the hood at the left hand end of slot 214. This slot has a length or arcuate extent of 120°, the projection 218 has an arcuate extent of 82° and the stop 219 intercepts an arc of 30°.

Referring now to the diagrammatic illustration of the dial 237 and associated parts, in Figure 10, when the parts are in the positions shown in Figures 2 and 3, the pointer 236 is at the "pilot" mark, indicated by the letter P of the dial, and pin 212 is at the left hand or clockwise end of slot 214. In order to set the control device for operation, the adjusting screw 201 is turned in a counter-clockwise direction in an arc of approximately 120° so as to be threaded outwardly of nipple 200. That causes outward or upward movement of adjusting stem 202, permitting adjusting lever 105

to be swung upward about shaft 108 by the compression spring 112. During this upward movement of lever 105 shaft 103 contacts finger 100 of the reset and trip lever 92, swinging this lever in clockwise direction about shaft 93 and depressing stem 82, thereby moving valve member 48 and stem 49 thereof downward in opposition to the compression spring 62, such a distance as to bring the armature 66 (Figure 9) into contact with the pole ends of magnet frame 69, or substantially so. Valve member 48 is then held in its full open position by the adjusting screw, and the fuel or gas may flow freely into housing 35 and thence through tube 115 to the pilot burner 28, which is then ignited. The flame of the pilot burner impinging upon the thermocouple 27 heats the latter sufficiently to energize the coil 77 of the electromagnet which, when energized, holds the armature 66 in attracted position and thus holds the safety valve member 48 in open position in opposition to compression spring 62. The positions occupied by the valve member 48 and the parts associated therewith, when this valve member is in its full open position, are indicated in dotted lines in Figure 9. After the electromagnet has been energized by the heat of the pilot burner flame so as to hold the valve member 48 in open position, the key 235 is released and torsion spring 222 turns adjusting screw 201 in clockwise direction, as viewed in Figure 2, through an arc of 120°, returning pin 212 to its normal position at the left or clockwise end of slot 214, the hood 215 remaining in position with the right hand end of extension 218 thereof in contact with stop 219. The pilot burner is now lighted and the electromagnet is energized, conditioning the control means for regulating flow of fuel to the main burner as permitted by the adjusting means and the thermostat.

When the pilot burner has been lit and the resetting operation has been effected, with the safety valve member 48 being held in its open position, as above described, the adjusting lever 105 is in its position shown in Figure 3 and the reset and trip lever 92 is in its position indicated by dotted lines in that figure. Shaft 103 is then disposed between fingers 100 and 101 in spaced relation to both thereof. The main burner valve 155 is then in its closed position shown and the lever 125 is held depressed by the pressure of regulating lever 118 exerted on finger 124, by the downward pressure exerted by the thermostat. In the depressed or lowered position of lever 125, the mid-portion of leaf spring 145 is engaged between the upper end of stop screw 152 and the under face of depressed element 140 of extension 139 of lever 125, the end portions of spring 145 being then flexed downward. In the depressed position of lever 125 the finger 170 of arm 168 of the main burner valve lever 135 is spaced a short distance above lever 125, as shown more clearly in Figure 6.

In order to admit gas to the main burner, the adjusting screw 201 is turned from the pilot position of Figure 10 in a clockwise direction through an arc of approximately 60°, to the main burner position, indicated by the letters "MB." That moves the adjusting lever 105 downward a short distance about shaft 108, in opposition to compression spring 112. This downward movement of lever 105 also causes downward movement of the regulating lever 118 and thereby reduces the downward pressure exerted by the thermostat, particularly compression spring 180 thereof, sufficiently to permit upward movement of the main

burner valve operating lever 125 by leaf spring 145, supplemented by compression spring 153. When the pressure exerted by lever 118 on finger 124 has been sufficiently reduced, as explained, the end portions of leaf spring 145 will flex upward with a snap action. That projects lever 125 upward and this lever, in its upward travel, strikes finger 170 of arm 168 a sharp blow, thus moving the lever 135 with lever 125 in the remaining upward travel of the latter lever. In that manner the main burner valve 155 is opened with a snap action, which is desirable as assuring proper opening of that valve. Valve 155 is opened but a slight distance, sufficient to supply gas to the main burner in proper amount for low or dim operation of that burner. By turning adjusting screw 201 a further distance in clockwise direction, the adjusting lever 105 is moved downward a corresponding distance relieving the pressure exerted by lever 118 on tongue 124, thus permitting further upward movement of lever 125 and corresponding increase opening of valve 155. In that manner the amount of gas delivered to the main burner may be varied to suit requirement. The extent to which the adjusting screw 201 may be turned in clockwise direction for increasing the opening of valve 155 is approximately 43°, throughout which the valve 155 remains under control of the thermostat.

The range of the thermo-control of valve 155 is indicated by the arrow and by the letters "TC" adjacent thereto, in the diagram of Figure 10. In the full open position of valve 155, under control of the thermostat, the furnace has a heating capacity such that the return air flowing through passage 15 may have a maximum temperature of approximately 85° F. Throughout the range of the thermo-control of the valve 155, extending from the "MB" mark on the dial through a range of approximately 43°, the main burner valve 155 is under control of the thermostat. If the temperature of the return air tends to exceed the temperature for which the control is set, the expansive force of the thermo-sensitive fluid within the thermostat increases the downward pressure exerted upon lever 118, thus moving lever 125 downward with corresponding downward movement of the lever 135 and valve 155, thus reducing the amount of gas flowing through the main burner until the desired temperature has been restored. If the excess temperature is considerable, the main burner valve 155 may be closed, thus extinguishing the main burner, but the safety shutoff valve 48 remains open assuring supply of gas to the pilot burner so that, when the temperature has been sufficiently reduced and the main burner valve 155 is again opened, the gas flowing from the main burner will be ignited by the pilot burner.

In the closing of the main burner valve 155, the downward pressure exerted on tongue 124 of lever 125, by lever 118, increases until it overcomes the compression spring 153 and, subsequently, the leaf spring 145, the end portions of which then flex downward with a snap action. That results in quick downward movement of lever 135, the result being that the closing movement of the valve 155 is modulated and this valve, in the final stage of the closing movement thereof, is closed with a snap action, which is desirable as assuring closing of the main burner valve 155 in a manner effective to shut off all flow of gas to the main burner. It will be seen that I have thus provided means whereby the main burner valve 155 is opened and closed by a snap action,

with the advantages referred to, this valve being under control of the thermostat throughout the thermo-control portion of the operation of the control means.

By turning the adjusting screw 201 in clockwise direction a further distance, beyond the thermo-control area of the diagram of Figure 10, the point of extension 118 of adjusting lever 105 is brought into contact with leaf spring 171 secured on arm 168 of the main burner valve lever 135. Continued turning of screw 201 in clockwise direction depresses lever 105 and, through member 117, moves the main burner valve 135 downward in closing direction, in opposition to compression spring 153. In that manner the main burner valve 155 may be closed, or moved in closing direction, manually and independently of the thermostat, the latter still being capable, however, of moving the main burner valve 155 in closing direction responsive to a temperature in excess of that for which that valve has been manually adjusted. The manual control of the main burner valve may extend through a range of approximately 115°, as indicated by the arrow marked "MC" on the diagram of Figure 10. When the pointer 236 reaches the position C on the diagram of Figure 10, the main burner valve 155 is in its fully closed position, to which it has been moved manually by turning of the adjusting screw 201 in clockwise direction. By turning adjusting screw 201 a further distance in clockwise direction, beyond the C position on the dial, shaft 103 is moved into contact with finger 101 of the reset and release lever 92. Thereafter, continued turning of screw 201 in clockwise direction turns lever 92 about shaft 93 in counterclockwise direction, as viewed in Figure 3, thus forcing valve stem 82 upward and with it safety shutoff valve member 48, valve stem 49 and armature 66. That pulls the armature 66 away from the pole ends of the magnet frame 69 (Figure 9) thus releasing the armature from the electromagnet, and the compression spring 62 then moves safety shutoff valve 48 upward into its fully closed position, moving the armature 66 into its fully retracted position, as shown in Figure 9. This release and closing of the safety valve member 48 occurs when the pointer 236 reaches the position indicated by T on the dial, approximately 30° clockwise from the position C on the dial.

From what has been said, it will be clear that by turning the adjusting screw 201 in counterclockwise direction, the safety shutoff valve 48 is reset from its closed position to its open position, for supplying fuel to the pilot burner, and, after the pilot burner has been lighted and the thermocouple has been heated sufficiently to energize the winding of the electromagnet so as to hold valve member 48 in its open position, turning of adjusting screw 201 in clockwise direction opens the main burner valve 155, which is then under control of the thermostat throughout a predetermined range of further turning of screw 201 in clockwise direction, the control being then automatic and remaining so if desired. By continuing to turn adjusting screw 201 in clockwise direction, beyond the thermo-control range of the device, the main burner valve may be adjusted manually and, if desired, closed, continued turning movement of adjusting screw 201 in clockwise direction resulting in closing the safety shutoff valve and thus shutting off supply of fuel to the pilot burner also, if desired. It will also be clear that by turning the adjusting screw 201 in counterclockwise direction, as viewed in Figure 10, from any point in the manual control range on the dial,

without having first turned this screw clockwise beyond the C position on the dial to any point on the thermo-control area of the dial, the main burner may be again placed under control of the thermostat. The adjusting screw 201 and associated parts thus provide simple and effective means for adjusting the control device as desired and for placing the main burner valve either under control of the thermostat or under manual control. Also, by continued turning movement of the adjusting screw 201 in clockwise direction, the safety shutoff valve 48 may be released and closed, as above described. Once that has been done, no gas can enter the housing 35 until the resetting operation has been effected.

In order to effect the resetting operation, after safety shutoff valve 48 has been tripped manually, the adjusting screw 201 is turned in a counterclockwise direction from the T position of the dial to the P position thereof, after which the resetting is effected in the manner above described. During turning of screw 201 counterclockwise, from position T to position P, the main burner valve 155 will be opened by compression spring 153, during the travel of pointer 236 over the manual control area of the dial, and will be in its full open position when the pointer is at the "TC" position on the dial. But in the continued turning of screw 201 counterclockwise, the valve 155 will be moved in closing direction, during travel of pointer 236 over the thermo-control area of the dial, and when the pointer reaches a position slightly beyond the "MB" position on the dial, counterclockwise thereof, valve 155 is closed with a snap action and remains closed during the resetting operation, as previously described. That eliminates possibility of flow of fuel to the main burner until the resetting operation has been completed, even though valve 155 be reopened, since no fuel can enter housing 35 until the safety shutoff valve 48 has been opened and opening of valve 155 during the resetting operation is prevented, as has been explained.

It will be understood that the range or extent of movement of the adjusting screw 201 for effecting the various conditions above referred to may be varied considerably by altering the proportions of the various parts of the control device and, therefore, are used for purposes of description only and are not in any sense limiting. In any event, however, continuous movement of the adjusting screw in one direction, that is, clockwise direction as viewed in Figure 10, effects the several conditions of the control means in successive order, which is conducive to simplicity and accuracy in operation. It is also possible, by means of this adjusting screw, to place the main burner valve under either thermal control or manual control, as desired, and to effect the tripping operation and the resetting operation of the safety shutoff valve, in the manner described.

The thermostat means of Figure 3 may be replaced by the thermostat means of Figure 8, for regulating flow of fuel to the main burner responsive to temperature variations at a point remote from the furnace. In that respect, it will be understood that the bulb 267 of the thermostat means of Figure 8 may be disposed at any suitable location remote from the furnace and within a room or space to be heated by the furnace, the main burner valve 155, when under control of the thermostat means, regulating flow of fuel to the main burner in accordance with temperature variations to which the bulb 267 is subjected. Since the operation of the control

means utilizing the thermostat means of Figure 8 is otherwise the same as the operation of the control means shown in Figure 3, no detailed description of the operation of the control means embodying the thermostat means of Figure 8 is necessary.

As above indicated, and as will be understood by those skilled in the art, changes in construction and arrangement of parts of my invention may be resorted to without departing from the field and scope thereof, and I intend to include all such variations, as fall within the scope of the appended claims, in this application in which the preferred forms only of my invention have been disclosed.

I claim:

1. In control means of the character described, a housing having an inlet and an outlet, a safety shutoff valve controlling said inlet, condition responsive means for holding said valve open responsive to a first condition and closing it responsive to a second condition, a second valve controlling said outlet, thermoresponsive means, and adjusting means comprising connecting levers between said valves whereby said adjusting means is effective for optionally placing said second valve under control of said thermoresponsive means and under manual control in the normal operating condition of said control means with said safety shutoff valve held open.

2. In control means of the character described, a housing having an inlet and an outlet, a safety shutoff valve controlling said inlet, condition responsive means for holding said valve open responsive to a first condition and closing it responsive to a second condition, a second valve controlling said outlet, thermoresponsive means, and adjusting means comprising connecting levers between said valves whereby said adjusting means is effective for optionally placing said second valve under control of said thermoresponsive means and for moving said second valve in closing direction independently of said thermoresponsive means in the normal operating condition of said control means with said safety shutoff valve held open.

3. In control means of the character described, a housing having an inlet and an outlet, a safety shutoff valve controlling said inlet and yieldingly urged in closing direction, electromagnetic means effective when energized for holding said valve in open position, a second valve controlling said outlet, a thermostat, adjusting means comprising connecting levers between said valves whereby said adjusting means is effective for optionally placing said second valve under control of said thermostat and for moving said second valve in closing direction independently of said thermostat in the normal operating condition of said control means with said safety shutoff valve held open, and means supplementary to said adjusting means effective for releasing said safety shutoff valve from said holding means when said second valve has been closed by said adjusting means and for resetting said safety shutoff valve to its open position independently of said second valve.

4. In control means of the character described, a housing having an inlet and an outlet, a safety shutoff valve controlling said inlet and yieldingly urged in closing direction, electromagnetic means effective when energized for holding said valve in open position, a second valve controlling said outlet, a thermostat, an adjusting member movable in two directions, and means supplementary to said adjusting member comprising connecting

levers between said valves whereby said adjusting member is effective for moving said safety shutoff valve from its closed position to its open position responsive to movement of said member in one direction and for thereafter successively placing said second valve under control of said thermostat, under control of said adjusting member in the normal operating condition of said control means with said safety shutoff valve held open, closing said second valve and releasing said safety shutoff valve from said holding means, in the movement of said adjusting member in its other direction.

5. In control means of the character described,

15 a housing having an inlet and an outlet, a safety shutoff valve controlling said inlet and yieldingly urged in closing direction, electromagnetic means effective when energized for holding said valve in open position, a second valve controlling said 20 outlet, a thermostat, adjusting means comprising an adjusting member movable in two directions, and connecting levers between said valves whereby said adjusting member is effective when moved in one direction for resetting said safety shutoff valve to its open position and effective when moved in the other direction for successively placing said second valve under control of said thermostat, under control of said adjusting member in the normal operating condition of said 25 control means with said safety shutoff valve held open, closing said second valve and releasing said safety shutoff valve from said holding means.

6. In control means of the character described, 30 a housing having an inlet and an outlet, a safety shutoff valve controlling said inlet, condition responsive means for holding said valve open responsive to a first condition and closing it responsive to a second condition, a second valve controlling said outlet, thermoresponsive means, and 35 adjusting means comprising connecting levers between said valves whereby said adjusting means is effective for optionally placing said second valve under control of said thermoresponsive means and under manual control in the normal 40 operating condition of said control means with said safety shutoff valve held open, and for releasing said safety shutoff valve from said holding means and resetting said safety shutoff valve from its closed position to its open position independently of 45 said second valve.

7. In control means of the character described, 50 a housing having an inlet and an outlet, a safety shutoff valve controlling said inlet, yieldingly urged in closing direction, electromagnetic means 55 capable when energized of holding said valve open, a second valve controlling said outlet, and adjusting means comprising an adjusting member movable in opposite directions from a pre-determined position and connecting levers between said valves whereby in said position of said member both of said valves are closed and movement of said adjusting member in one of said directions is effective for resetting said safety shutoff valve to its open position independently 60 of said second valve and movement of said member in the opposite direction is effective for opening said second valve and continued movement of said adjusting member in said opposite direction is effective for closing said second valve, 65 and thereafter releasing said safety shutoff valve from said holding means with resulting closing of said latter valve.

8. In control means of the character described, 70 a housing having an inlet and an outlet, a safety shutoff valve controlling said inlet yieldingly

urged in closing direction, electromagnetic means capable when energized of holding said valve open, a second valve controlling said outlet yieldingly urged in opening direction, a thermostat, and adjusting means comprising an adjusting member movable in opposite directions from a predetermined position and connecting levers between said valves whereby in said position of said member both of said valves are closed and movement of said member in one of said directions is effective for resetting said safety shutoff valve to its open position independently of said second valve and movement of said member in the opposite direction is effective for opening of said second valve and placing it under control of said thermostat and continued movement of said member in said opposite direction is effective for placing said second valve under control of said member and further movement of said member in said opposite direction is effective for closing said second valve and thereafter releasing said safety shutoff valve from said holding means with resulting closing of said latter valve.

9. In control means of the character described, a housing having an inlet and an outlet, a safety shutoff valve controlling said inlet yieldingly urged in closing direction, electromagnetic means capable when energized of holding said valve open, a second valve controlling said outlet, a thermostat, an adjusting lever having a position in which both of said valves are closed and movable in opposite directions from said position, means comprising a manually operable adjusting member effective for adjusting said lever in either direction, and means whereby adjustment of said lever in one direction effects resetting of said safety shutoff valve to open position while preventing opening of said second valve during the resetting operation and movement of said lever in the opposite direction effects opening of said second valve and placing thereof under control of said thermostat.

10. In control means of the character described, a housing having an inlet and an outlet, a safety shutoff valve controlling said inlet yieldingly urged in closing direction, electromagnetic means capable when energized of holding said valve open, a second valve controlling said outlet, a thermostat, an adjusting lever having a position in which both of said valves are closed and movable in opposite directions from said position, means comprising a manually operable adjusting member effective for adjusting said lever in either direction, and means whereby adjustment of said lever in one direction effects resetting of said safety shutoff valve to open position while preventing opening of said second valve during the resetting operation and movement of said lever in the opposite direction successively effects opening of said second valve and placing thereof under control of said thermostat, placing of said second valve under control of said lever, and closing of said second valve and thereafter mechanical release of said safety shutoff valve from said holding means with resulting closing of said latter valve.

11. In control means of the character described, a housing having an inlet and an outlet, a safety shutoff valve controlling said inlet yieldingly urged in closing direction, electromagnetic means capable when energized of holding said valve open, a second valve controlling said outlet yieldingly urged in opening direction, a thermostat, an adjusting lever, connections between said lever and said second valve and said ther-

mostat effective for causing closing of the latter and opening thereof under control of said thermostat responsive to adjustment of said lever, a safety shutoff valve reset and release lever having lost motion connection to said adjusting lever, said latter lever having a position in which both of said valves are closed and being movable in opposite directions from said position, and means for adjusting said adjusting lever in opposite directions, said connections comprising means whereby movement of said adjusting lever in one direction effects resetting of said safety shutoff valve to open position while preventing opening of said second valve during the resetting operation and movement of said adjusting lever in the other direction effects opening of said second valve and placing thereof under control of said thermostat.

12. In control means of the character described, a housing having an inlet and an outlet, a safety shutoff valve controlling said inlet yieldingly urged in closing direction, electromagnetic means capable when energized of holding said valve open, a second valve controlling said outlet yieldingly urged in opening direction, a thermostat, an adjusting lever adjustable in opposite directions, an operating lever connected to said second valve, a regulating lever pivoted on said adjusting lever subject to pressure exerted by said thermostat and bearing on said operating lever for urging said second valve in closing direction, a safety shutoff valve reset and release lever having lost motion connections to said adjusting lever, said latter lever having a position in which both valves are closed and being movable in opposite directions from said position, and means for adjusting said adjusting lever in opposite directions, the parts being so related that adjustment of said adjusting lever in one direction effects resetting of said safety shutoff valve to open position while preventing opening of said second valve during the resetting operation and movement of said adjusting lever in the opposite direction effects opening of said second valve and placing thereof under control of said thermostat and continued movement of said adjusting lever in said opposite direction successively places said second valve under control of said adjusting lever, closes said second valve and mechanically releases said safety shutoff valve from said holding means with resulting closing of said latter valve.

13. In control means of the character described, a housing having an inlet and an outlet, a safety shutoff valve controlling said inlet yieldingly urged in closing direction, electromagnetic means capable when energized of holding said valve open, a second valve controlling said outlet yieldingly urged in opening direction, a lever carrying said second valve, an operating lever for said second valve having lost motion connections to said carrying lever, an adjusting lever movable in opposite directions, means for adjusting said adjusting lever in opposite directions, a thermostat, means whereby both of said valves are closed in one position of said adjusting lever and movement thereof in one direction away from said position effects resetting of said safety shutoff valve to open position while preventing opening of said second valve during the resetting operation and movement of said adjusting lever in the opposite direction effects opening of said second valve and placing thereof under control of said thermostat, and means associated with said second valve operating lever for im-

parting thereto a snap action in its initial movement in valve opening direction and its final movement in valve closing direction whereby said second valve is opened and closed with a snap action.

14. In control means of the character described, a housing having an opening, a valve carrying lever, a valve carried by said lever controlling said opening, a valve operating lever having a depressed element and an element underlying said depressed element defining therewith a passage, a leaf spring extending through said passage with its ends remote therefrom and loosely connected to said operating lever, means yieldingly urging said operating lever upward, means for moving said operating lever downward, said underlying element having an opening therethrough, and an

abutment member disposed to extend through said opening and cooperating with said depressed element to clamp therebetween the mid-portion of said spring as said operating lever approaches the limit of its downward movement whereby the portions of said spring beyond said abutment member are flexed downward with a snap action and in the initial upward movement of said operating lever said portions of said spring are flexed upward with a snap action effective for imparting a snap action to said operating lever in the final downward movement and the initial upward movement thereof, and connections between said valve carrying lever and said operating lever for imparting to the former the snap actions of the latter.

LOURDES V. McCARTY.
